TELEPHONE SYSTEM

Application filed November 25, 1927, Serial No. 235,438, and in Germany February 12, 1927.

The invention relates to telephone systems, in which the release of a connection is initiated by alternating current impulses.

When in such installations alternating current of audible frequency is used for the impulse transmission, there is the possibility of the connection being released by speech currents. Now the invention is to prevent such faults occurring in the service, this being achieved in a simple manner in that time switching devices, which are controlled by incoming alternating current impulses of audible frequency, prevent the connecting device being released when the duration of the impulses exceed or do not reach a certain time limit.

By way of example the invention is shown a system, in which the positioning of the switches is effected by an operator over a long junction line and the release is brought about automatically by an alternating current impulse of audible frequency when the connection is released at the operator's position.

Referring now to the drawing comprising Figs. 1 and 2, only such apparatus in a system embodying the features of the invention has been shown as is necessary to enable the invention to be understood. Fig. 1 of the drawing shows the equipment at the operator's position or originating end of the junction line and Fig. 2 shows the equipment at the automatic office or terminating end of the junction line.

In Fig. 1 the cord circuit is represented by the plug St, which when inserted into a jack K takes into use the junction line having the leads La and Lb going to an automatic exchange. The junction line is isolated at both ends by means of voice current repeaters, hence alternating current is used for the impulse transmission. In order that the alternating current impulses shall be efficiently repeated, alternating current of audible frequency is used for the impulse transmission.

The method of operating will now be described with reference to the drawing.

When the operator at the outgoing end of the junction line has been requested to set up a connection with a subscriber of the

automatic exchange reached over the junction line, she inserts the plug St into the jack K of Fig. 1. Thereby the relay B that is connected to the sleeve of the jack is energized, and at contact 1 b it closes a circuit for the relay C 1 in series with the resistance W 1. In known manner the operator now switches over a not shown selecting switch, over which the impulse sender is connected to the leads of the plug. The alternating current impulses pass over the springs of the jack K, back contacts 15 a and 16 a to the primary winding of the repeater Ue₁, they are then repeated over the leads La and Lb of the junction line to the repeater Ue 2, Fig. 2, and thence over a chain of filters SK tuned to the frequency of the selecting impulses to the amplifier VSt. After being amplified, they then reach the alternating current relay R. The latter at contact 5 r closes a circuit for the relay J, which at the contact 6 j closes the circuit of the succeeding switches each time an impulse is transmitted. At the same time the contact 7 j establishes the following circuit for the relay C 2: earth, contacts 7 j, 8 y, relay C 2, contacts 9 c 2, 10 y, resistance W 2, battery, earth. The relay C 2 is operated and at its contact 12 c 2 it closes a locking circuit for itself. At the same time the contact 9 c 2 removes the short circuit from the winding of the relay Y. The latter is operated. At its contact 8 y it opens the circuit for energizing the relay C 2 and at the contact 20 y it short circuits the winding of the relay C 2. But this cannot fall back, as the positioning impulses are of short duration and the armature of the relay C 2 falls back slowly owing to its winding being short circuited. Thus on receiving positioning impulses, the contact 7 j is opened before the relay C 2 has fallen back. When the relay Y operates, its contact 17 y prepares the circuit of the second time switching device, which

comprises a relay Z and a resistance W 3 connected in parallel therewith. When the relay C 2 was operated, the contact 11 c 2 closed a circuit for the release relay, which is connected to the testing and blocking lead and belongs to the succeeding switch. When the relay Y is operated, its contact 14 y 100

bridges over the contact 11 c 2. The switch is then positioned in known manner.

At the end of the conversation, the operator withdraws the plug St from the jack K, Fig. 1, thus releasing the relay B. The latter at its contact 19 b short circuits the winding of relay C 1 and at contact 3 b it closes a circuit for the relay A extending over the contact 4 c. Hence the relay A is energized until the relay C 1 falls back, which it does slowly owing to the winding of C 1 being short circuited. The alternating current source WQ, which has a definite audible frequency, is connected over the contacts 15 a and 16 a to the junction line going to the automatic exchange. This alternating current impulse, which is long compared with the positioning impulses, energizes the relay R, Fig. 2, at the incoming end of the junction line and thus a circuit for the relay J is closed at the contact 5 r. Relay J switches over its contact 7 j, thereby short circuiting the winding of relay C 2 over the contacts 20 y and 22 z. At the same time the contact 18 j prepares a circuit for the relay Z, which however, is only established when the relay C 2 falls back and closes the contact 13 c 2. This circuit extends from earth over the contacts 18 j, 13 c 2, 17 y, winding of relay Z in parallel with resistance W 3 to battery and earth. The relay Z attracts its armature slowly owing to the comparatively low ohmic resistance being connected in parallel with it. The releasing impulse is of such length that it is terminated after the release of the relay C 2 and before the relay Z has operated. When the relay C 2 then falls back, the contact 11 c 2 removes earth from the testing and blocking lead to the succeeding switch, but the latter for the present remains connected up over the contact 14 y. However, the opening of the contact 12 c 2 interrupts the circuit of the relay Y, hence this also falls back and effects the final removal of ground from the testing and blocking lead.

If the release impulse be too short, the relay C 2 is not short circuited long enough for it to fall back. On the other hand if the alternating current impulse be too long, the relay Z is operated as above described and thus a fresh circuit is established for the relays C 2 and Y over the contacts 20 y and 21 z. At the end of the current impulse, the contacts 7 j and 18 j are opened; hence the relay Z falls back, while the locking circuit for the relays C 2 and Y is maintained over the contact 12 c 2.

From the foregoing it can be seen that an unintentional release of the connection by speech currents is avoided, because only an alternating current of closely limited duration can bring about the release.

What is claimed is:

1. In an electroresponsive mechanism, means for receiving an impulse of current,

means effective upon the cessation of the impulse for causing a predetermined operation of the mechanism, timing means for timing the duration of the impulse for a given period of time, additional timing means initiated into operation upon the expiration of said period of time for timing the duration of said impulse for an additional period of time, and means effective if the duration of the impulse is less than said first period of time or greater than both of said periods of time for rendering said first named means ineffective. 70 75

2. In an electroresponsive mechanism, means for receiving an impulse of current, two successively operated timing means each for timing the duration of the impulse for a predetermined period of time, and means effective if the impulse of current ceases during the timing by the second operated means for causing a predetermined operation of the mechanism. 80 85

3. In an electroresponsive mechanism, means for receiving an impulse of current, successively operated minimum and maximum timing means for timing the duration of the impulse, and means effective if the impulse ceases after the operation of the minimum timing means and before the operation of the maximum timing means for causing the operation of the mechanism. 90 95

4. In an electroresponsive mechanism, means for receiving an impulse of current, successively operated minimum and maximum timing means for timing the duration of the impulse, and means effective if the duration of the impulse exceeds the minimum time and is less than the maximum time for causing the operation of the mechanism. 100

5. In an electroresponsive mechanism, means for receiving an impulse of current, timing means for timing the duration of the impulse, and means controlled by the timing means and effective if the duration of the impulse exceeds a predetermined minimum amount of time and is less than a predetermined maximum amount of time for causing the operation of the mechanism. 105 110

6. In an electroresponsive mechanism, means for receiving an impulse of current, means effective upon the cessation of the impulse for causing a predetermined operation of the mechanism, means for timing the duration of the impulse, and means effective if the duration of the impulse exceeds a predetermined maximum period of time for rendering the first named means and the mechanism unaffected by the impulse. 115 120

7. In an electroresponsive mechanism, means for receiving an impulse of current, means effective upon the cessation of the impulse for causing a predetermined operation of the mechanism, means for timing the duration of the impulse, and means effective if the duration of the impulse exceeds a predeter- 125 130

mined maximum period of time for rendering the first named means ineffective.

8. In an automatic switch wherein an impulse of current brings about the release of the switch, time delayed means for rendering the impulse of current ineffective if its duration exceeds a predetermined period of time.

9. In an automatic switch, means for receiving an impulse of current, means effective upon the cessation of the impulse for causing the release of the switch, and means effective if the duration of the impulse exceeds a predetermined maximum period of time for rendering said first named means ineffective.

10. In a telephone system wherein the release of an existing connection is brought about by an impulse of alternating current of audible frequency impressed upon the talking conductors, means for preventing the release during the continuance of the impulse, and timing means for preventing the release if the duration of the impulse is less than a predetermined minimum or exceeds a predetermined maximum period of time.

11. In a telephone system wherein the release of an existing connection is brought about by an impulse of alternating current of audible frequency impressed upon the talking conductors, a slow-to-respond relay controlled by the impulse of current, means effective upon the response of said relay for rendering the release of the mechanism dependent upon the cessation of the impulse, and timing means effective a predetermined period of time after the response of said relay for preventing the release of the connection if the release has not already taken place.

12. In a telephone system wherein the release of an existing connection is controlled by an impulse of current, a slow-to-respond relay controlled by the impulse of current, means effective upon the response of said relay for rendering the release of the connection dependent upon the cessation of the impulse, and timing means dependent upon the continuance of the impulse for a predetermined period of time for preventing the release of the connection by said impulse.

13. In a telephone system wherein the release of an existing connection is brought about by an impulse of current, means for preventing the release during the continuance of the impulse, and timing means for preventing the release if the duration of the impulse is less than the predetermined minimum or exceeds a predetermined maximum period of time.

In witness whereof, I hereunto subscribe my name this 26th day of October, A. D. 1927.

MAXIMILIAN MATHIAS.
